UNITED STATES PATENT OFFICE.

GEORGE C. HODGDON, OF ALLEGHENY, PENNSYLVANIA.

REFRIGERATOR.

SPECIFICATION forming part of Letters Patent No. 251,881, dated January 3, 1882.

Application filed November 15, 1880. Renewed July 6, 1881. (Model.)

To all whom it may concern:

Be it known that I, GEORGE C. HODGDON, of Allegheny city, in the county of Allegheny and State of Pennsylvania, have invented certain new and useful Improvements in Refrigerators; and I do hereby declare the following to be a full, clear, and exact description of the invention, such as will enable others skilled in the art to which it pertains to make and use it, reference being had to the accompanying drawings, which form part of this specification.

My invention relates to an improvement in refrigerators; and it consists in the introduction of an ice-receptacle entirely surrounded by passages for air, which receptacle can be removed and replaced at pleasure without difficulty.

It has heretofore been customary to make the ice-receptacles fixtures in the refrigerators, removable only with great difficulty, and seldom without injury to some parts of the refrigerators. By my improvement the ice-receptacle can be drawn out without trouble, and when removed from the refrigerator nothing prevents a thorough washing and cleaning of all parts, which is so essential in places where milk, butter, meat, and other victuals are kept for preservation from the effects of a heated atmosphere.

The accompanying drawings represent my invention.

Figure 1 is a front elevation of my refrigerator. Fig. 2 is a vertical section of the same. Fig. 3 is a plan view of the ice-box alone.

The box A represents the refrigerator. It has a rabbeted close-fitting door, B, that occupies the whole front, leaving a small aperture or vent on top for the escape of heated air from below. The lower two-thirds of the space in the box A are to be occupied by perforated shelves for the support of substances to be kept cool, which shelves may be taken out at pleasure.

Within the box A, and attached to its rear side, is a water-pipe, b, with an enlarged upper end or funnel under the bottom of the frame D, which frame laterally occupies the space in the box A to within a short distance of its sides, rear, and front.

Hinged to one of the uprights C of the frame

D is a rabbeted non-conducting door, E, which door, when closed, is flush with the uprights C, leaving an open space or flue between it and the outer door, B. The uprights C, reaching as high as the box allows, project at the sides of the frame D, and with a projecting piece, d, at the rear, guide the frame when taken out or pushed into place and keep it at a distance from the walls of the box A.

On the frame D are ribs i, extending from side to side, and on them rests the bottom of a pan, h, that is fastened in front to the frame. This pan h forms the bottom of the ice-receptacle F, whose perforated vertical walls m are secured to the inner sides of the uprights C, which walls inclose the sides and rear of the receptacle and rest in the pan.

By means of the ribs i air passages or channels are made under the ice-box, and thus a better circulation is kept up and a larger cooling-surface attained.

The front of the receptacle F is closed by the hinged door E, that is somewhat lower than the uprights C, leaving a space on top open for the passage of air; and the holes in three sides or walls of the receptacle also permit air to pass downward after being cooled by the ice.

From the pan h leads a short pipe down to the enlarged upper end of the pipe b, through which water collected in the pan is carried off.

It will be seen from the foregoing that the ice-receptacle is entirely isolated, and that the air, after being raised to a higher temperature from being in contact with objects in the lower portion of the refrigerator, rises and escapes through the vent on top of the outer door, while the cooler air from the ice takes its place below. The object of the inner door, E, is to prevent the entrance of warm air into the ice-receptacle when the door B is opened to put in or take out things from the shelves.

The capacity of the refrigerator may be increased by the addition of one or more ice-receptacles side by side, arranged to pass ice from one to the other, with non-conducting walls separating the space below. If this be done, the door of but one chamber need be opened at a time; hence the temperature in those that remain closed will not be affected.

By removing the ice-receptacle from the re-

frigerator when not needed as such the box A is made a convenient cup or side board.

Having thus described my invention, I claim—

5 In a refrigerator, the combination of the frame A, the support D, having the ribs *i*, the ice-box F, having perforated sides *m*, and provided with the door E, the box being made removable from the frame, and a space left all

around the box for the free circulation of air, to substantially as shown.

In testimony that I claim the foregoing I have hereunto set my hand this 24th day of February, 1880.

GEORGE C. HODGDON.
